Primary Examiner — Melanie Pellegrini(74) Attorney, Agent, or Firm — Wilson Sonsini Goodrich & Rosati(57) CLAIM

The ornamental design for a ring, as shown and described.

DESCRIPTION

FIG. 1 is a top front perspective view of a ring, showing my new design;

FIG. 2 is a bottom front perspective view thereof; and, FIG. 3 is a top rear perspective view thereof.

The broken lines shown in the drawings represent portions of the ring that form no part of the claimed design.

1 Claim, 2 Drawing Sheets(56)
